UNITED STATES PATENT OFFICE

HARRY F. SMITH, OF DAYTON, OHIO, ASSIGNOR TO THE GAS RESEARCH COMPANY, OF DAYTON, OHIO, A CORPORATION OF OHIO

GAS PRODUCER

Original application filed January 30, 1922, Serial No. 532,724. Divided and this application filed December 10, 1923. Serial No. 679,603.

This invention relates to gas generation, and more particularly to the generation of producer gas.

One of the principal objects of the invention is to provide such a small size producer as is adapted for the generation of gas for domestic use, which is simple and cheap in its construction, and efficient in operation.

Another object of the invention is to provide a small size producer with means for cutting down the heat losses during operation.

Other objects and advantages of the invention will be apparent from the description thereof set out below when taken in connection with the accompanying drawing.

This is a division of the copending application of Harry F. Smith, Serial No. 532,724, filed January 30, 1922, now Patent No. 1,724,525, dated August 13, 1929.

20 In the drawing, in which like characters of reference designate like parts throughout the several views thereof:

Fig. 1 is a vertical sectional view through a form of gas producer; and

25 Fig. 2 is a vertical sectional view of still another modified form of producer.

The producers heretofore in general use have, ordinarily, run in size in excess of twenty-five horsepower, most of them running several hundred horsepower and some of them several thousand horsepower. The producers shown in the drawing and described herein, are, however, primarily designed for the furnishing of gas for domestic

30 or home use, and are of considerably smaller size than those heretofore in general use. Where these producers are designated, therefore, as being of "small size" it is meant that they are normally of less than twenty-five

35 horsepower, and generally of from three to ten horsepower. Or to illustrate in another way, the grate diameter of the producers heretofore in general use have ranged in diameter from three to sixteen feet, whereas the producers which are herein designated as small size have, in general, a grate diameter of not more than twelve inches.

40 In the copending application of Harry F. Smith, No. 398,749 dated July 24, 1920, is described a form of producer adapted for the

supplying of gas for operating small size gas engines, such as are found in the well-known house-lighting plant, and for supplying gas for domestic use. In the type of producer shown therein a single shell is provided which contains both the gas generating zone, in which the active fuel bed is located, and the fuel reservoir, in which fuel for a considerable period of operation is contained.

45 In the types of gas producers shown herein the fuel reservoir is made separate and distinct from the generator of the producer, the size of the generator thus being considerably less than in the type of producer shown in the above referred to copending application. 55 Also the fuel container can be made of considerably lighter metal than the material of the generator. As a consequence the weight of the entire apparatus is materially less, a feature which is quite advantageous where the 60 producer is to be exported, and in addition the initial manufacturing expense is materially decreased.

55 Every producer is provided with some means for preventing heat losses from the 75 fuel bed by radiation from the shell of the producer into the atmosphere. Where producers of the size heretofore generally used, in excess of three feet in diameter, are provided with conventional fire brick lining, the 80 ratio of the radiating surface of the shell to the mass of incandescent fuel in the fuel bed is so low that these radiation losses are not particularly objectionable, although they do of course decrease the efficiency of the producer.

85 But in a small sized gas producer, such as illustrated and described herein, in which the grate diameter is probably not in excess of twelve inches, and some of the forms of producer shown herein having been 90 operated successfully with grate diameters of four inches, the ratio between the radiating surface of the shell and the mass of incandescent fuel in the generating chamber is so great that if the heretofore generally 95 prevalent methods of heat insulating lining are used the heat losses by radiation from the shell will be so great as to not only seriously interfere with the satisfactory operation of the producer, but to even com-

pletely prevent the operation of that producer in such wise as to make a combustible gas. It is generally true that the greater the heat loss in a producer the less the percentage of combustible constituent in the gas, and if the heat losses become sufficiently high the fuel may be completely consumed without the generation of any combustible gas at all, there being merely complete combustion of the fuel into carbon dioxide.

Therefore, in these small size producers the lining has been so constructed that transfer of heat therethrough into the shell is minimized, and the grate has also been so constructed that it has no direct thermal connection with the shell of the producer. As a result producers of the small size mentioned above, constructed in accordance with the disclosure of this application, will during ordinary operation show an efficiency as high as, or even higher than, the efficiency of the best of the large size producers.

In the producer shown in Fig. 1, however, the conventional lining is entirely dispensed with, and instead the ingoing blast is so introduced that it absorbs the heat tending to escape from the fuel bed into the shell, and carries that heat back into the fuel bed.

As illustrated the gas producer consists of a lower section 10, which comprises a cylindrical shell open at its upper end; and an upper section, comprising a cylindrical tube 11, of less diameter than the shell 10, and adapted to be positioned within that shell, this tube, when the generator is completely assembled, containing the gas generating chamber 12. Surrounding the tube 11 is a circular chamber 13, which functions as a vaporizer, this chamber, upon its lower wall, being provided with a circular grooved member 14, the groove in this member being adapted to receive the upper end of the shell 10, suitable packing 15 being positioned therein, so that when the two are in assembled position a tight joint is maintained to prevent leakage of air into the producer, or of gas out from the producer. Depending from the lower wall 16, of the chamber 13, is a circular flange 17, so proportioned that it will lie within the shell 10, and be spaced a suitable distance therefrom. Attached to the inner wall of the shell 10 is a shelf 20, which carries an upstanding flange 21, which is smaller in diameter than the depending flange 17, and is thus, when the device is assembled, positioned between the flange 17, and the cylindrical tube 11. The construction is such that the flange 17 extends downwardly such a distance that it terminates a short distance from the shelf 20 while the flange 21 extends upwardly such a distance that it terminates a short distance below the bottom plate 16. Water is supplied to the vaporizer, so as to maintain a constant water level therein, by means of, what for purposes of descrip-

tion is called, a "chicken feed" apparatus. This apparatus consists of a pipe 18, one end of which opens into the lower part of the vaporizer, and the other end of which is enlarged to receive the lower end of the bottle 19, which is in turn supported in any suitable manner, as by means of the standard 23. Obviously the level of the water in the vaporizer will be dependent upon the level of the water in the pipe 18, which in turn depends upon the position of the lower end of the bottle. And if the level of water in the vaporizer falls, the level of the water in the enlargement of the pipe 18 will also fall, the lower end of the bottle will be uncovered and a flow of water from the bottle into the enlargement, and through pipe 18 into the vaporizer, will take place.

Leading off from the vaporizer, through the upper wall thereof is a pipe 26, which opens into a nozzle 27, which may be of any suitable character. This nozzle projects into the upper open end of a pipe 30, the lower end of which opens into the space between the shell 10 and the depending flange 17.

During operation of the producer air passes in through the pipe 30, the producer being constructed to operate under suction. At the same time the vapor or steam generated within the vaporizer 13 passes through the nozzle 27 into the ingoing air. The amount of vapor which passes into the air may be controlled by proper manipulation of the needle valve 28. The exact construction of this nozzle 27 and needle valve 28 is not shown inasmuch as any conventional type of spray nozzle or needle valve may be used.

Because of the construction described above the ingoing blast is caused to travel downwardly between the shell 10 and the depending flange 17, thence upwardly between the flange 17 and the flange 21 and thence downwardly again between the flange 21 and the cylindrical tube 11 into the ash pit 33, and thence through the grate into the generating chamber, the generated producer gas passing outwardly through the offtake pipe 34. As the blast thus passes to the ash pit it absorbs the heat which tends to travel by conduction and radiation from the fuel bed through the tube 11 and flanges 21 and 17 to the shell 10. Thus the heat which tends to escape from the fuel bed is absorbed by the ingoing blast and carried back into the fuel bed so that, in final analysis, the heat losses are as inconsequential as in the heretofore known type of apparatus described above.

In this construction a grate 35 is provided, which consists of a perforated plate supported upon legs, and which is so arranged as to be out of thermal connection with the shell of the producer.

In Fig. 2 is shown a modified form of pro-

ducer. In this modification are combined a lining of heat insulating material, with a construction of the character shown in Fig. 1, in which the ingoing air blast is caused to absorb the heat which tends to pass from the fuel bed to the shell of the producer. In this form of producer a layer of heat insulating material 50 is provided, a metallic tube 51, which may be of any suitable metal, but is preferably of some metal which is highly resistant to oxidation, and other chemical reactions, at high temperatures, such a metal, for example, as some of the chromium and nickel alloys is positioned within the gas generating chamber of the producer, and spaced from the layer of heat insulating material. Interposed between the cylindrical tube 51, and the layer of insulating material 50 is a metallic member 52, which as shown is made of cast iron and which is provided with a series of inwardly extending ribs 53 so positioned that a series of circular grooves or passages 54 are provided.

The ribs 53 are so constructed that when the tube 51, and the member 52 are placed in position, these ribs will contact with the tube 51, the grooves 54 thus becoming closed passages. Each of the ribs 53 has an opening 55 therein, these openings being so arranged that they are in staggered relation. Opening into the uppermost of the passages 54 is a blast inlet pipe 60, through which the blast of air and moisture is introduced into this uppermost groove. This producer as shown, is adapted to operate under either pressure or suction, and during operation the blast introduced into the uppermost passage 54 will move downwardly from one passage to the next, through the openings 55, its path of travel, and, therefore, the time during which it is brought in contact with the tube 51 being thus lengthened so that it may absorb a greater quantity of heat during its travel through these passages. The heated blast passes out through the lowermost of the openings 55 into the ash pit and then upwardly into the fuel bed, the resulting producer gas passing off through the offtake pipe 61. The pipe 60 should be attached to some form of saturator, or apparatus in which the air for the blast is caused to take up the proper proportion of moisture. The precise construction of the saturator is not shown, since saturators of this character are well-known. If desired a construction similar to that shown in Fig. 1, or a saturator such as that shown in the patent to Harry F. Smith, No. 888,359 dated May 19, 1908, which shows a saturator which has worked very satisfactorily for a number of years, can be used.

In both the modification shown in Fig. 1 and that shown in Fig. 2 the ingoing air blast as it passes into the generating chamber is caused to absorb heat from the fuel bed,

and carry that heat back into the generating chamber. Any suitable means may be used for causing a blast to pass through the fuel bed. The offtake pipe may be connected to a suitable pump, or directly to a gas engine, in both of which cases the producer will be suction operated. If desired the producer may be pressure operated in which case a suitable pump or blower is used for forcing the blast through the generating chamber, and the fuel bed therein, under pressure.

While the method herein described, and the forms of apparatus for carrying this method into effect, constitute preferred embodiments of the invention, it is to be understood that the invention is not limited to this precise method and forms of apparatus, and that changes may be made in either without departing from the scope of the invention which is defined in the appended claims.

What is claimed is:

1. A gas producer of the character described, comprising a cylindrical lower section; an upper section comprising a cylindrical tube of small heat capacity and of less diameter than the said lower section, the said upper section seating upon the upper end of the lower section in gas-tight contact, with the cylindrical tube thereof arranged within the lower section, coaxially therewith, and spaced from the inner wall thereof; a cylindrical flange depending from the said upper section into the lower section, and spaced from the said lower section; a cylindrical upstanding flange carried by the said lower section and extending upwardly into the space between the said depending flange and the said tube carried by the upper section; and means for introducing a blast of air and moisture into the space between the wall of the lower section and the depending flange carried by the upper section, whereby the blast as it passes to the fuel bed within the tube carried by the upper section, is forced to pass in heat transferring relation downwardly around the depending flange carried by the upper section, thence upwardly around the upstanding flange carried by the lower section, and thence downwardly again around the tube carried by the upper section into the fuel bed, to prevent the transfer of heat from the fuel bed through said tube into the atmosphere.

2. A domestic gas producer of the character described, comprising a metallic tube of small heat capacity adapted to contain a fuel bed of carbonaceous material therein, a shell surrounding said tube in spaced relation thereto and coaxially therewith, a plurality of concentric upright partitions interposed between said shell and said tube, said parts forming a staggered passage about the exterior of said tube, a blast inlet pipe opening at one end into said staggered passage, the opposite end of said pipe being open to

atmosphere, a steam generator within the upper end of the shell and surrounding said tube in heat conducting relation therewith, a water inlet pipe for said steam generator, said water inlet pipe having an upturned end, an inverted water container supported with its mouth within said upturned end, a nozzle directly connected to the interior of said steam generator, said nozzle discharging into the upper end of said blast pipe, and valve means for controlling the quantity of steam passing from the steam generator through said nozzle into said blast pipe, said parts being adapted to pass the blast of air and moisture in a staggered path in heat conducting relation around said partitions and over the outer wall of said tube as it travels to the fuel bed, to prevent the transfer of heat from the fuel bed through said tube into the atmosphere.

3. A gas producer of the character described, comprising a metallic shell, an inner tube spaced therefrom providing a gas generating chamber adapted to contain a fuel bed of incandescent carbonaceous material, a plurality of concentric upright partitions interposed between the shell and the said tube and spaced therefrom and from each other, the space between said tube and the partition immediately surrounding said tube having communication with said gas generating chamber, and the spaces between partitions being in staggered communication with each other and in communication with said first mentioned space, whereby a staggered connected passage around said partitions is provided, water vapor generating means in heat transferring relation with said producer, an air inlet for said producer, and means for causing said air and water vapor to circulate through said staggered passage as it travels to the fuel bed to thereby heat said air and water vapor prior to its introduction into the fuel bed.

45 In testimony whereof I hereto affix my signature.

HARRY F. SMITH.
